UNITED STATES PATENT OFFICE.

GUSTAV STRUCK, OF BERLIN, GERMANY.

STARTING DEVICE FOR HYDROCARBON-ENGINES.

SPECIFICATION forming part of Letters Patent No. 619,238, dated February 7, 1899.

Application filed March 26, 1898. Serial No. 675,235. (No model.)

To all whom it may concern:

Be it known that I, GUSTAV STRUCK, manufacturer, a subject of the King of Prussia, German Emperor, residing at No. 30 Stettinerstrasse, Berlin, in the Kingdom of Prussia, German Empire, have invented a new and useful Starting Device for Hydrocarbon-Engines, of which the following is a full, clear, and exact specification.

This invention relates to a device for starting hydrocarbon-engines. The general purpose of my invention is to start any number of such engines by means of one and the same crank, provided said engines be furnished with certain combinations and arrangements of parts, such as are described hereinafter. In general these parts constitute one half of a coupling, the other half of which is attached to or forms part of the boss of the crank aforementioned. Besides the general purpose aforementioned, a particular purpose of the same consists in preventing the operator from being hurt in case the explosion of the mixture of gas and air occurs too early, so that the shaft of the engine is driven in the reversed direction.

In order to make my invention more clear, I refer to the accompanying drawings, in which similar letters denote similar parts throughout the different views, and in which—

Figure 1 shows that part of the coupling which is secured to the shaft of the engine. Fig. 2 shows a side view of the coupling. Fig. 3 shows the other part of the coupling. Fig. 4 is a section in line 6 7 of Fig. 1, and Fig. 5 shows a side view of a sleeve forming part of the first-mentioned half of the coupling.

My improved device or coupling is constructed as follows: A crown-wheel *c*, Figs. 1, 2, and 4, with ratchet-teeth *b'* and forming a kind of collar or boss, is secured to one end of the driving-shaft of the hydrocarbon-engine, the connection being preferably effected by a spindle or bolt *h*, having a screw-threaded part *h'*. This part *h'* takes into a correspondingly-threaded bore of the shaft of the engine. The spindle or bolt *h* may be used as a pivot or guide for the other half of the coupling.

The reduced part of the crown-wheel *c* is encompassed by a sleeve *d*, Figs. 1, 2, 4, and

5, provided with ratchet-teeth *d'* around its periphery. These teeth coöperate with a pawl *g*, Fig. 1, attached to a suitable part of the frame of the engine. The sleeve *d* is provided with two recesses or cuts *e*, Figs. 1, 4, and 5, located diametrically one to the other. The boss *a*, Figs. 2 and 3, of the crank *i* constitutes the other half of the coupling 60 and forms also a crown-wheel with ratchet-teeth *b*, Fig. 3. The number and position of these teeth *b* correspond to the number and position of the teeth *b'*, the arrangement being such that the teeth *b* and *b'* mesh with each other when the boss or crown-wheel *a* is shoved upon the bolt or spindle *h*, and the direction of inclination of the ratchet-teeth *b* being such that the crown-wheel *c* is turned by the crown-wheel *a* when the crank *i* is 70 moved in the direction of the hands of a clock, and the shaft of the engine will also be turned by means of the crown-wheel or collar or boss *c*.

The crown-wheel or boss *a* is furnished with 75 two rolls *f*, the number and position of which correspond to the number and position of the cuts or recesses *e* of the sleeve *d*. Before or while shoving the boss *a* upon the bolt *h* the parts *a* and *d* are so arranged with regard 80 to each other that the rolls *f* take into the recesses *e*, as otherwise the teeth *b* cannot take into the teeth *b'*.

When the engine has been started, by turning its driving-shaft by means of the device 85 aforementioned, the speed of that shaft will soon increase and the crown-wheel *c* will thus turn quicker than the crown-wheel *a*, the speed of motion of the latter being of course dependent on the speed of the crank *i*. In consequence of the difference in speed thus occurring the teeth *b'* will glide along the teeth *b*, thus displacing the boss *a* in the direction of the free end of the bolt *h* until the coupling between the two parts *a* and *c* is interrupted, 90 when the crank may simply be drawn off said bolt.

If the mixture of gas and air should explode 100 too early, so that the shaft of the engine is turned in the reverse direction, the movement of teeth *b'* will counteract the movement of teeth *b* and the crank *h* will receive a heavy shock, so that the operator may easily be hurt. To prevent such an accident, the toothed

sleeve *d* and the pawl *g* have been provided. When the crown-wheel *c* is turned in the reverse direction by the shaft of the engine, the sleeve *d* will be prevented by the pawl *g* 5 against turning together with the wheel. Owing thereto the rolls *f*, which are secured to the crown-wheel *a*, and are thus caused to revolve when this wheel is turned, will thus be compelled to roll along the inclined surfaces 10 constituting the recesses *e*, so that finally they leave these recesses. While this takes place, the teeth *b* are drawn out of the teeth *b'*, so that consequently the coupling between the two parts *a* and *c* is automatically interrupted. The compulsory movement imparted 15 to the crank *i* is thus but very short, and is, in fact, so short that an accident cannot possibly result therefrom.

Having thus fully described the nature of 20 my said invention, what I desire to secure by Letters Patent of the United States is—

In a starting device for hydrocarbon-engines, the combination with a crown-wheel *c* with ratchet-teeth *b'*, secured to the driving-shaft of the engine, of another crown-wheel *a* with ratchet-teeth *b*, forming the boss of a crank, and adapted to mesh with said former wheel; a sleeve *d* having ratchet-teeth located around its periphery, and encompassing the wheel *c*; recesses *e* provided in said sleeve, 25 rolls *f* attached to the wheel *a* and arranged so as to take into said recesses and a pawl *g* attached to the engine and arranged so as to coöperate with the ratchet-teeth of the sleeve, 30 substantially as described.

In witness whereof I have hereunto set my hand in presence of two witnesses.

GUSTAV STRUCK.
